UNITED STATES PATENT OFFICE.

MICHAEL BERARDINI, OF NEW YORK, N. Y.

CHECK, DRAFT, AND SIMILAR INSTRUMENT.

No. 845,923.

Specification of Letters Patent.

Patented March 5, 1907.

Application filed March 21, 1906. Serial No. 307,148.

To all whom it may concern:

Be it known that I, MICHAEL BERARDINI, a citizen of the United States, a resident of Fort Wadsworth, Staten Island, county and

5 borough of Richmond, city and State of New York, have invented certain new and useful Improvements in Checks, Drafts, and Similar Instruments, of which the following is a specification.

10 My invention relates to commercial instruments—such as checks, drafts, and the like—and has for its object to facilitate and simplify the keeping of proper records by the bank or other party issuing such instruments 15 and also the provision of a proper record for all of the parties concerned in the transaction.

I have devised my present improvement with especial reference to the conditions 20 arising when a customer purchases from a banker a draft to be paid by another banker and where the issuing banker is supposed to advise his correspondent on whom the draft is made of the amount of each draft and certain other particulars. Heretofore a great 25 deal of bookkeeping has been required in such cases; and the object of my present invention is to reduce such bookkeeping to a minimum.

30 For this purpose my invention consists of certain features fully described hereinafter and particularly pointed out in the claims.

Reference is to be had to the accompanying drawings, in which—

35 Figure 1 is a face view of a draft-pad embodying my invention. Fig. 2 is a face view of one of the duplicates, and Fig. 3 is a section taken on line 3 3 of Fig. 1.

The improved pad comprises a large sheet 40 A, which is intended to be retained by the issuing banker, one or more smaller sheets B, exactly alike, which are intended for transmission to the banker's correspondent, and, finally, a draft-sheet C of about the same size 45 as the sheets B and subdivided by lines of perforations C' into a series of draft-blanks C². These draft-blanks are preferably provided with consecutive numbers in the spaces C³, and also have a space C⁴ for the insertion

50 of the amount, another space C⁵ for the remitter's name, a space C⁶ for the payee's name, and a space C⁷ for the payee's residence. This arrangement may of course be varied to suit the individual conditions of the business. The draft-blanks shown are such 55 as have been used by me, though they are

not in the usual and well-known form, and it is to be understood that any form of draft may be used that will best suit individual requirements.

60 Each of the sheets B may be slightly larger than the sheet C, and on the projecting portion B' may be a space for writing in the name of the banker's correspondent on whom the drafts are made, with the date, and 65 the number of the pad. Each of the sheets B is divided by vertical lines B² into a series of columns, the first of which from the left in Fig. 2 may bear a number, the second the amount designated in dollars, francs, lire, 70 marks, &c., and the third, fourth and fifth may be headed, respectively, "Remitter," "Payee," and "Payee's residence." The said sheets B may be further divided into a series of rows by horizontal lines B³. The lines B³ 75 correspond to the lines of perforations separating the drafts C² from each other and the lines B² to the division-lines provided in each draft. The lines on the sheets B might be omitted, as the user will soon become familiar with the proper meaning of entries according to their position. Under the heading "Number" the same numbers as are used on the drafts C² will be reproduced. The last sheet A has a portion which is an 80 exact duplicate of the sheets B and has in addition thereto at the left an extension A'. This extension is subdivided by horizontal lines into a series of spaces which contain the same numbers as the drafts, and also is provided with a number of blank spaces in 85 which various items may be entered, such as the name and address of the party paying for the draft, the cash received in the currency of the realm, the commission charged, 90 the amounts in foreign money corresponding to the drafts, and the figures showing the amount of business brought forward from previous pads, as well as the total of the amounts of the pad. The sheets B and C 95 are fastened to the sheet A to the right of the extension A' in any suitable manner, as by staples D, and are preferably perforated adjacent to the point where they are secured, 100 as indicated at B⁸ C⁸.

105 In using my invention sheets of carbon-paper are placed between each two of the sheets of the pad, and then the drafts C² are filled out in the customary way. It will be readily seen that the entire writing of the 110 draft is reproduced at once on each of the sheets A and B. The only other entry which

is made at the time is on the extension A' of the sheet A, where the amount of United States money received, the commission charged, and the name and residence of the 5 party paying for the draft would be entered, or, in brief, any such particulars as do not appear on the draft itself. The draft will then be handed to the purchaser or his agent, and when the sheet of drafts has been filled up 10 the proper date and pad-number will be written at the top of each sheet B, together with the name of the correspondent. The sheet B will be torn off and sent to such correspondent, who will thus receive a complete 15 and clear record of all drafts which may be presented to him for payment. In the example shown there are two sheets B, so that a duplicate may be sent to the correspondent by a different mail; and it will be understood 20 that if triplicate copies are desired three sheets B will be provided and that in some cases one such sheet will be considered sufficient. The writing put at the top of the sheet B is reproduced, by means of the carbon- 25 paper, not only on the duplicate sheet B, but also on the sheet A. This latter sheet is kept by the issuing banker and is of such a nature that it may be readily bound together with other sheets of the same kind 30 to form a book which will constitute a complete record of all transactions of this character. The figuring of the totals of the cash received, commission received, and amounts of the drafts expressed both in the currency 35 of the realm and in the currency of the country on which they are issued may be

figured and entered as soon as a draft-sheet has been used up or at any convenient time thereafter.

I claim as my invention—

1. A pad for drafts and other commercial instruments, consisting of a plurality of sheets one of which is wider than the others which are secured to said wide sheet at a distance from one of its edges, such other, 45 narrower sheets comprising a sheet having consecutively-numbered draft-forms, and an additional sheet having consecutively-numbered portions, the wider sheet also having consecutively-numbered portions, and the 50 registering or superposed portions of all the sheets being subdivided alike into spaces adapted to receive corresponding entries.

2. A pad for drafts and other commercial instruments, consisting of a wide sheet, another sheet narrower than the first-named sheet and superposed on a portion thereof, and a further sheet of substantially the same width as the second-named sheet but of smaller height, all of said sheets being 55 secured together and the superposed portions of all the sheets being subdivided in a like manner so as to receive identical entries in corresponding places by the use of interposed sheets of carbon-paper.

In testimony whereof I have hereunto signed my name before two subscribing witnesses.

MICHAEL BERARDINI.
